DRAWER OPERATING MECHANISM

Carl F. Mayer, Lakewood, Ohio

Application December 31, 1947, Serial No. 795,045

5 Claims. (Cl. 214—18)

1

This invention relates to industrial ovens of the drawer type that are used in foundries and other plants for baking or drying cores and molds, or for heat treating other articles. Because of the weight of the drawers and their contents, ovens of this type incorporate drawer operating mechanism comprising a track that extends beyond the front plane of the oven casing or housing a distance somewhat greater than the projected distance of a fully opened drawer. A trolley traverses the track and supports a column that mounts coupling means by which the drawers may be selectively connected to the column.

Objects of the invention are to provide, in drawer operating mechanism of the sort referred to, improved means for coupling the drawers to the column, which means is simple of construction; is effective in making and retaining connection with a drawer; is thoroughly reliable and durable in service, and is convenient and comparatively easy of manipulation, notwithstanding the fact that in its operation it lifts and sustains the otherwise unsupported forward end of a drawer that is especially heavy when loaded.

The foregoing objects and advantages, with others hereinafter appearing, are attained in the embodiment of the invention illustrated in the accompanying drawings, and while I shall proceed to describe said embodiment in detail, it will be understood that the invention is not thus limited, but is commensurate in scope with the claims appended hereto.

In the drawings,

Fig. 1 is a front elevational view of a drawer type oven incorporating my improvements;

Fig. 2 is a fragmentary plan view thereof;

Fig. 3 is a sectional side elevation of the oven structure, showing one of the drawers fully open and the drawer operating mechanism in the position it occupies under such conditions, the said mechanism being indicated in dot-and-dash lines in retracted position;

Fig. 4 is a detail, in side elevation, of the coupling means for connecting a drawer to the column of the drawer operating mechanism, the present view showing said means in effective position, as when coupling a drawer to the column and sustaining the forward end of the drawer slightly above its normal elevation;

Fig. 5 is a view, similar to Fig. 4, showing said coupling means in ineffective position;

Fig. 6 is a front elevational view of the drawer coupling means, in the position shown in Fig. 5, and

Fig. 7 is a sectional detail on the line 7—7 of Fig. 6.

2

The oven structure, designated generally by the reference numeral 1, comprises a rectangular casing or housing constructed of insulated walls of the kind commonly employed in such structures, the top wall being designated 2, the bottom wall 3, the opposite side walls 4 and 5, and the rear wall 6. The front wall 7 is provided with rectangular openings for the passage of the drawers generally designated 10, 11 and 12. The casing or housing is supported a suitable distance above the floor 15, by legs 16.

Each of the drawers 10, 11 and 12 includes a front 50 that is provided on its outer side adjacent the bottom thereof with drawer pulls 51, each drawer having two pulls that are laterally spaced apart a suitable distance. The bottom 52 of the drawer is in the form of a grid and is connected at its forward end to the front 50 adjacent the lower edge of the latter. Rising from the bottom 52 in forwardly spaced relation to the rear end thereof is a seal plate 53. Connected in an approved manner to the rear end of the drawer bottom, so as to roll therealong, is an axle 54. Wheels 55 are attached to the ends of the axle 54 and travel along rails 58 that are supported by and between the front and rear walls of the oven.

60 is a carriage equipped with flanged wheels 61 that traverse rails 62. These rails comprise a track that is embedded in the floor 15 and extends from beneath the oven forwardly a distance somewhat greater than that represented by a fully opened drawer. Suitably secured to and rising from the front of the carriage 60 is a column designated generally by the reference numeral 65. This column is shown as consisting of side members 66 that are connected together at their upper ends by a cross member 67.

Carried by the column 65 are coupling means, generally denoted 70, for selectively connecting the drawers 10, 11 and 12 to said column. Referring particularly to Figs. 4 to 7, each of the coupling means 70 includes a rock shaft 71 that is journaled in bearings 72 and 73 that are secured, by bolts 74, to the side members 66 of the column 65. Fastened to the ends of the rock shaft 71 outwardly beyond the bearings 72 and 73 are relatively short arms 75 the ends of which, remote from the shaft, have pivotal connection with the upper ends of links 76. The lower ends of these links are similarly connected to the forward ends of levers 78 that are pivotally mounted on a rod 80 that is disposed crosswise of the column 65 and is supported by being extended through openings in the members 66. The levers 78 are held on the rod by abutment means or collars 81 that are fastened to the rod outwardly beyond

the levers and in such spaced relation to the members 66 as to insure freedom of movement of the levers. The rear ends of the levers 78 are shaped to provide hooks 85 for upward engagement within the downwardly opening sockets of the drawer pulls 51.

It will be observed that the bearings 72 are longer than the bearings 73 and that they project inwardly a distance beyond the adjacent side member 66 of the column 65 where they are provided with radial notches 86 and 87. The notches, in each case, open through the end as well as the peripheral surface of the bearing and are spaced substantially 90° apart, the notch 86 being at the top, and notch 87 at the front. Secured to the rock shaft 71, in practically abutting relation to the bearing 72, is the hub 89 of a relatively long arm 90, shown as formed at its outer end with a grip portion or handle 91. Projecting radially from the hub 89 in the same direction as the arm 90 and intermediate said arm and the end of the hub adjacent the bearing 72 is a lug 93 to which is pivoted, by means of a pin 94, a latch member 95. The nose of the latch member is adapted to occupy one or the other of the notches 86 and 87, and extending freely through an opening in the end of the latch member remote from the nose thereof is a rod 96 that has its inner end opposite a recess 97 in the hub 89 and its outer end guided through a hole in the handle 91, beyond which said rod terminates in a head 98. Where the rod extends through the opening in the latch 95, it is pivotally connected to the latch by means of a pin 99. A helical spring 100, that surrounds the end portion of the rod 96 adjacent the hub 89 and seats, at one end, in the recess 97, is compressed between the bottom of the recess and the overhanging portion of the latch 95. Accordingly, said spring tends to rock the latch in a direction to engage its nose within one of the notches of the bearing 72, and the latch is moved in opposition to the spring by pressure applied to the head 98. In order that it may better withstand lateral strain, the nose of the latch is confined between ears 101 that project radially from the hub 89 on opposite sides of a notch normally occupied by a portion of the nose.

When the drawers are closed, as is usually the case, the portion of the carriage rearwardly of the column 65 is beneath the casing or housing with said column closely adjacent the front wall 7. Also, under these circumstances, the arms 90 of the coupling means 70 are held in vertical position by engagement of the latches 95 in the notches 86 of the bearings 72.

When it is desired to open a drawer for loading or unloading it, the coupling means 70 that corresponds to the selected drawer is operated in the following manner: The handle 91 of the arm 90 is grasped, in the doing of which the head 98 of the rod 96 is depressed against the action of the spring 100 to rock the latch 95 in a direction to withdraw its nose from the notch 86 of the bearing 72. With the arm thus released, it is swung down to a horizontal position, as shown in Fig. 6. This results in the shorter arms 75 being similarly moved and, by reason of the latter's connection through the links 76 with the levers 78, the front ends of said levers are swung downwardly so as to elevate the hooks 85 on the rear ends of the levers and engage them within the sockets of the drawer pulls 51. These inter-engaging parts are so proportioned and related that, as the arms 75 and 90 approach horizontal

position, the hook 85 strikes the top wall of the sockets of the drawer pulls 51 and lifts the forward end of the drawer enough to remove its weight from the bottom of the drawer opening in the front wall 7. Now, by removing pressure from the head 98 of the rod 96, the spring 100 will be permitted to rock the latch 95 in a direction to engage its nose within the notch 87 of the bearing 72 and lock the parts in their present 5 positions with the front of the drawer held elevated. The full weight of the drawer, with that 10 of any articles thereon, will be sustained by the rollers 55 and the carriage 60. Consequently, the drawer may be easily opened by pulling on the 15 handle 91 so as to cause the carriage 60 to travel to the front end of the track comprising the rails 62; and, when the drawer is fully extended, the drawer opening in the front wall 7 will be closed by the seal plate 53. With the drawer open it 20 may be loaded or unloaded in the usual way and if a load of considerable weight is involved, it may be readily handled by means of an overhead hoist or crane since the space above the drawer is entirely unobstructed. The drawer is closed 25 by reversing the foregoing operation and, when fully closed, the major portion of the carriage 60 is beneath the oven casing or housing and the column 65 adjacent the front wall 7 thereof. Now the latch 95 may be released and the coupling means 70 restored to its former position wherein 30 it is held by the engagement of the latch 95 in the notch 86.

Having thus described my invention, what I claim is:

35 1. In drawer operating mechanism, in combination with a column adapted for disposition adjacent the front of a drawer provided with a drawer pull, coupling means comprising a lever pivoted intermediate its ends to the column, the rear end of the lever being shaped for holding engagement with the drawer pull, a shaft supported by the column at an elevation vertically spaced from the horizontal plane of the pivot of said lever, a relatively short arm fixed to the shaft, a link connecting the outer end of said 40 arm to the forward end of the lever, a second and longer arm secured to the shaft for rocking it thereby to engage the rear end of the aforesaid lever with the drawer pull when the longer arm is in one position and to disengage it therefrom when said longer arm is in a second position, and latch mechanism incorporated in the longer arm and cooperating with a part fixed with respect to the column for holding the coupling means against movement when said longer 45 arm is in either of said positions.

50 2. Coupling means for drawer operating mechanism according to claim 1, wherein said longer arm is provided with a handle at its outer end, and said latch mechanism includes 55 actuating means contiguous to said handle.

60 3. In drawer operating mechanism, in combination with a column adapted for disposition adjacent the front of a drawer provided with a 65 pair of laterally spaced drawer pulls, coupling means comprising two levers each pivoted intermediate its ends to the column, the rear end of each lever being shaped for holding engagement with one of said drawer pulls, a shaft supported by the column at an elevation vertically spaced from the horizontal plane of the pivotal axes of 70 said levers, a relatively short arm fixed to the shaft adjacent each end thereof, a link connecting the outer end of each arm to the forward 75 end of the corresponding lever, a longer arm se-

cured to the shaft for rocking it thereby to engage the rear ends of the aforesaid levers with the drawer pulls when the longer arm is in one position and to disengage them therefrom when said longer arm is in a second position, and latch mechanism incorporated in the longer arm and cooperating with a part fixed with respect to the column for holding the longer arm against movement when in either of said positions.

4. Coupling means for drawer operating mechanism according to claim 3, wherein said longer arm is provided with a handle at its outer end, and said latch mechanism is adjacent the inner end of the longer arm and includes actuating means contiguous to said handle.

5. In drawer operating mechanism, in combination with a column adapted to be disposed adjacent the front of a drawer provided with a drawer pull, coupling means comprising a lever pivoted intermediate its ends to the column, the rear end of said lever being shaped to constitute a hook for holding engagement with the drawer pull, a bearing on the column at an elevation vertically spaced from the horizontal plane of the pivotal axis of said lever, a shaft journaled in said bearing, a relatively short arm fixed to the shaft in substantially the vertical plane of said lever, a link connecting the outer end of said arm to the forward end of the lever, a second and longer arm secured to the shaft for rocking it thereby to engage said hook with the drawer pull when the longer arm is in one position and to disengage it therefrom when said longer arm is in a second position, the longer arm incorpo-

rating a hub that surrounds the shaft adjacent the aforesaid bearing, the bearing having in its end adjacent said hub notches that are spaced apart angularly of the bearing to correspond to the aforesaid positions of the longer arm, a latch pivotally connected to the hub and having a nose adapted for engagement within said notches, a spring tending to move the latch in a direction to engage its nose with a notch of the bearing, a rod carried by the longer arm and extending therealong and having its inner end operatively connected to the latch, the outer end of the longer arm incorporating a handle, and means on the rod adjacent said handle for moving the rod in a direction to release the latch in opposition to said spring.
